BY
P. T. Dodge
ATTORNEY

UNITED STATES PATENT OFFICE.

LUTHER L. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,080,349.

Specification of Letters Patent.

Patented Dec. 2, 1913.

Application filed August 14, 1912. Serial No. 714,961.

To all whom it may concern:

Be it known that I, LUTHER L. KENNEDY, a citizen of the United States, and a resident of Brooklyn, county of Kings, and State of 5 New York, have invented a new and useful Improvement in Typographical Machines, of which the following is a specification.

My invention relates to typographical casting machines, such as linotype machines 10 of the general organization represented in Letters Patent of the United States No. 436,532, to O. Mergenthaler, wherein circulating matrices are released from a magazine in the order in which their characters 15 are to appear in print, and then assembled in line, the composed line transferred to the face of a mold, the mold filled with molten metal to form a slug or linotype against the matrices which produce the type characters 20 thereon, and the matrices thereafter returned through a distributing mechanism to the magazine from which they started.

More particularly, the invention relates to the mold carrier or disk, which is ordinarily 25 provided with a plurality of molds of different style and dimensions, any one of which may be brought into operative relation to the other parts, as desired. The particular means whereby these adjustments 30 may be effected constitute no part of my present invention, and are or may be substantially like those employed in the commercial linotype, or as disclosed in Letters Patent of the United States to W. H. Randall, No. 758,103.

In machines of this kind, it is sometimes a matter of difficulty to ascertain which mold is in operation, and similarly to bring another selected mold into proper position. 40 For purposes of convenience and to obviate these difficulties, I have provided means, which indicate the particular mold in operation and also assist in substituting another one therefor, these means preferably consisting of properly located marks upon the mold carrier or wheel, which marks register with others on a stationary scale.

In the accompanying drawing, I have shown my improvement as applied to a linotype machine, but obviously it is capable of broader application, and may be employed in variant forms, which will suggest themselves to those skilled in the art, and in connection with other styles of typographical 55 machines, such, for instance, as those de-

signed to produce type and the like instead of slugs or linotypes, as in the present instance.

Generally speaking, I desire it to be understood that I do not limit myself to any 60 specific form or embodiment, except in so far as such limitations are specified in the claims.

The drawing is a front view of the mold wheel of a linotype machine, having my invention applied thereto.

The mold wheel A is of the usual construction and is shown as provided with four molds A¹, A², A³, and A⁴, any one of which may be brought into operative position in 70 the customary manner, for instance, by the actuating pinion B, as set forth in the said Randall patent. When the machine is in its normal position of rest, the operative mold is the one located at the right-hand side of 75 the wheel, in the present instance the mold A⁴.

In order that the operator may identify the mold, I provide a stationary scale or index S having marks thereon, which marks, in the present instance, are numbered 1, 2, 3, 4. I also provide the mold wheel with a series of marks a¹, a², a³, a⁴, each corresponding to one of the molds, and brought by the rotation of the mold wheel into registration 85 with one of the marks on the scale S. As previously pointed out, when the machine is at rest, the operative mold is located at the side of the wheel, or substantially 90° away from the scale. Therefore, the corresponding mark on the wheel must be located in advance of the mold and not in contiguity thereto. For instance, in the drawing the mold A⁴ is the operative one, and its corresponding mark a⁴ is at the top of the wheel. 90

The same arrangement is followed with reference to the other molds and corresponding marks, and, in order that they may register with those on the scale, the marks on the wheel are not only located in advance of their respective molds, but also their position is suitably varied circumferentially. Thus in the drawing, the mold A⁴ is the operative one, and its mark a⁴ registers with the mark 4 on the scale S, but if the wheel A be adjusted so as to bring another one into operative position, say the mold A², its corresponding mark a² will be brought to the top of the wheel and in registry with the mark 2 on the scale.

As previously stated, many variations and modifications of my invention will suggest themselves to those skilled in the art, and still be comprised within its scope.

Having thus described my invention, its construction and mode of operation, what I claim and desire to secure by Letters Patent of the United States is as follows:

1. In a typographical casting machine, the combination of an adjustable mold carrier provided with a plurality of molds, and having a like plurality of marks one for each mold, with a stationary scale having a corresponding series of marks, whereby the adjustment of the carrier to bring a mold into operative position simultaneously moves its mark into proper registry with the corresponding mark on the scale.

2. In a typographical casting machine, the combination of an adjustable rotary mold wheel provided with a plurality of molds, and having a like plurality of marks one for each mold and located out of contiguity thereto, with a stationary scale having a

corresponding series of marks, whereby the rotation of the wheel to bring a mold into operative position simultaneously moves its mark into proper registry with the corresponding mark on the scale.

3. In a typographical casting machine, the combination of an adjustable rotary mold wheel provided with a plurality of molds, and having a like plurality of marks one for each mold, located out of contiguity thereto and in varied circumferential positions on the wheel, with a stationary scale having a corresponding series of marks, whereby the rotation of the wheel to bring a mold into operative position simultaneously moves its mark into proper registry with the corresponding mark on the scale.

In testimony whereof I hereunto set my hand this eighth day of August, 1912, in the presence of two attesting witnesses.

LUTHER L. KENNEDY.
